(57) **CLAIM**

The ornamental design for a runner for ice skate, as shown and described.

DESCRIPTION

FIG. 1 is a side elevational view of a runner for ice skate in accordance with a first embodiment of our new design, shown mounted to an ice skate;

FIG. 2 is a perspective view thereof;

FIG. 3 is a top plan view thereof;

FIG. 4 is a bottom plan view thereof;

FIG. 5 is a right side elevational view thereof, the left side elevational view being a mirror image thereof;

FIG. 6 is a front elevational view thereof;

FIG. 7 is a rear elevational view thereof;

FIG. 8 is a cross-sectional view thereof, taken through line **8-8** in FIG. 5;

FIG. 9 is an enlarged partial cross-sectional view thereof, taken from region **9** in FIG. 8;

FIG. 10 is a cross-sectional view thereof, taken through line **10-10** in FIG. 5;

FIG. 11 is an enlarged partial cross-sectional view thereof, taken from region **11** in FIG. 10;

FIG. 12 is a cross-sectional view thereof, taken through line **12-12** in FIG. 5;

FIG. 13 is an enlarged partial cross-sectional view thereof, taken from region **13** in FIG. 12;

FIG. 14 is a cross-sectional view thereof, taken through line **14-14** in FIG. 5;

FIG. 15 is an enlarged partial cross-sectional view thereof, taken from region **15** in FIG. 14;

FIG. 16 is a cross-sectional view thereof, taken through line **16-16** in FIG. 5; and

FIG. 17 is an enlarged partial cross-sectional view thereof, taken from region **17** in FIG. 16.

FIG. 18 is a side elevational view of a runner for ice skate in accordance with a second embodiment of our new design, shown mounted to an ice skate;

FIG. 19 is a perspective view thereof;

FIG. 20 is a top plan view thereof;

FIG. 21 is a bottom plan view thereof;

FIG. 22 is a right side elevational view thereof, the left side elevational view being a mirror image thereof;

FIG. 23 is a front elevational view thereof;

FIG. 24 is a rear elevational view thereof;

FIG. 25 is a cross-sectional view thereof, taken through line **25-25** in FIG. 22;

FIG. 26 is an enlarged partial cross-sectional view thereof, taken from region **26** in FIG. 25;

FIG. 27 is a cross-sectional view thereof, taken through line **27-27** in FIG. 22; and

(Continued)

FIG. 28 is an enlarged partial cross-sectional view thereof, taken from region 28 in FIG. 27;
FIG. 29 is a cross-sectional view thereof, taken through line 29-29 in FIG. 22;
FIG. 30 is an enlarged partial cross-sectional view thereof, taken from region 30 in FIG. 29;
FIG. 31 is a cross-sectional view thereof, taken through line 31-31 in FIG. 22;
FIG. 32 is an enlarged partial cross-sectional view thereof, taken from region 32 in FIG. 31;
FIG. 33 is a cross-sectional view thereof, taken through line 33-33 in FIG. 22; and,
FIG. 34 is an enlarged partial cross-sectional view thereof, taken from region 34 in FIG. 33.
